Primary Examiner — Ricky Pham(74) Attorney, Agent, or Firm — Attentive Law Group; Paul Ratcliffe(57) CLAIM

The ornamental design for a hokie grill cover, as shown and described.

DESCRIPTION

FIG. 1 is a perspective view of a hokie grill cover of the present invention;

FIG. 2 is a front elevational view thereof;

FIG. 3 is back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The portions of the Figure shown in dashed lines are for illustrative purposes only and form no part of the claimed invention.
